CLAIM

The ornamental design for a data processing system, as shown and described.

DESCRIPTION

FIG. 1 is a top, front, right side isometric view of a data processing system, showing our new design;

FIG. 2 is a top, back, left side isometric view thereof;

FIG. 3 is a front elevational view thereof;

FIG. 4 is a top plan view thereof;

FIG. 5 is a right side elevational view thereof, the left side being identical;

FIG. 6 is a rear elevational view thereof;

FIG. 7 is a top, front, right side isometric view of a data processing system, showing another embodiment of our new design;

FIG. 8 is a top, back, left side isometric view thereof;

FIG. 9 is a front elevational view thereof;

FIG. 10 is a top plan view thereof;

FIG. 11 is a right side elevational view thereof, the left side being identical; and,

FIG. 12 is a rear elevational view thereof.

The bottom view of both embodiments of the data processing system are unornamented except for the inclusion of casters in the second embodiment. The two embodiments are identical in all respects except for the lower portion.
